UNITED STATES PATENT OFFICE.

ELIZABETH J. MAGEE, OF CHICAGO, ILLINOIS.

HAT-PIN-POINT PROTECTOR.

1,084,553.

Specification of Letters Patent.

Patented Jan. 13, 1914.

Application filed April 10, 1912. Serial No. 689,763.

To all whom it may concern:

Be it known that I, ELIZABETH J. MAGEE, a citizen of the United States, and a resident of the city of Chicago, county of Cook, 5 and State of Illinois, have invented certain new and useful Improvements in Hat-Pin-Point Protectors, of which the following is a specification.

My invention relates to improvements in 10 hat pin point protectors, and has for its object the production of a device of this character which will be of improved construction and efficient in use.

Other objects will appear hereinafter.

15 With these objects in view, my invention consists in the combinations and arrangements of parts hereinafter described and claimed.

My invention will be more readily understood by reference to the accompanying 20 drawing forming a part of this specification, and in which—

Figure 1 is a central longitudinal section of a hat pin point protector embodying my 25 invention, Fig. 2 is a section taken on line $\alpha\alpha$ of Fig. 1, and Fig. 3 is a detail perspective of one of the grasping jaw members of the device, detached.

The preferred form of construction, as 30 illustrated in the drawing, comprises a hollow body 1 which is open at both ends. The body 1 is formed of sheet metal and the same is formed enlarged at one end in order to add to the ornate appearance of the de-

35 vice. Pivotedly mounted at 2 in the opening provided at this end of said body are two coöperating jaw members 3. The inner ends of the jaw members 3 project into the body 1 for engaging against the opposite sides of 40 a hat pin point inserted between the same in order to lock said body upon the hat pin. Leaf springs 4 coöperate with the jaw members 3 for normally forcing the latter into 45 engaging or operative position, the engaging surfaces of said jaw members being pro-

vided with teeth, as shown, in order to increase the friction and so as to obviate the possibility of accidental displacement of the device from the pin point. The edge of the 50 opening at the end of the body is reinforced by a wire member 5 around which said end is bent, as shown, the wire member 5 serving as the pivot pin for each of the jaw members 3, the latter being provided with perforated 55 ears 6 which are engaged by the member 5, as clearly shown in Fig. 2. Arranged in the

opposite end of the body 1 is a cork member 7 which, however, forms no part of the present invention, is held in position by reason of the tapering form thereof, the adjacent 60 end of the body being formed to coincide, and by reason of the inwardly projecting flange 8 which is provided at the extremity of said end, the tapering walls of the body preventing movement of said member 7 in 65 one direction and the flange 8 preventing movement in the opposite direction. The member 7 serves to limit the inserting movement of a pin point when engaged by the jaw members 3, the cork, by reason of its 70 pierceability and resiliency, preventing any injury to the point of the pin which is forced into contact therewith. Also, if desired, the cork member 7 may be utilized in fastening the protector upon the pin point, the latter 75 being adapted to be inserted through the open end of the body 1 at the member 7 to pierce the latter, as shown in dotted lines in Fig. 1.

A protector of the construction set forth 80 is durable and economical and the same may be readily and quickly attached to a hat pin point and as expeditiously detached when desired. When positioned upon the point of a pin, the device will serve to guard or protect 85 the same so as to prevent injury, which might otherwise result with the pin point exposed. Also, the device will serve to prevent detachment of the hat pin and the consequent loss thereof.

While I have illustrated and described the preferred form of construction for carrying my invention into effect, this is capable of variation and modification without departing from the spirit of the invention. I, 95 therefore, do not wish to be limited to the exact details of construction set forth, but desire to avail myself of such variations and modifications as come within the scope of the appended claims.

Having described my invention, what I claim as new and desire to secure by Letters Patent, is:

1. In a device of the kind described comprising a metallic body portion having an open end; a ring turned in such metallic body portion around its open end; and two spring pressed coöperating pin clamping jaws pivoted on said ring, substantially as described.

2. A device of the kind described comprising a metallic body portion having an

2
open end; a ring turned in such metallic body portion around its open end; and two spring pressed coöperating jaws pivoted on said ring and having their manually operating ends extended from said body portion and their pin engaging ends extended inside said body portion, substantially as described.

In testimony whereof I have signed my name to this specification in the presence of two subscribing witnesses.

ELIZABETH J. MAGEE.
